UNITED STATES PATENT OFFICE.

KONRAD JAGSCHITZ, OF MAINZ, GERMANY, ASSIGNOR TO MASCHINENFABRIK AUGSBURG-NUERNBERG A. G., OF NUREMBERG, BAVARIA, GERMANY, A CORPORATION OF GERMANY.

GASOMETER.

Application filed February 26, 1926. Serial No. 90,980.

This invention relates to gasometers of the so-called disk type. Its object is to provide means by which a gasometer of this type may be enlarged so as to secure increased capacity without necessarily interrupting the continuity of its operation. Other more specific objects will appear from the description hereinafter and the features of novelty will be pointed out in the claim.

10 My invention is illustrated by way of example in the accompanying drawings, in which Fig. 1 is a vertical section of an improved and enlarged gasometer and Fig. 2 is a plan view thereof.

15 The gas holder shown in Fig. 1 consists of two polygonal sections A and B formed by a number of flat vertical panels *a*—*b*, the latter superimposed upon the former. A strengthening or stiffening member C is applied to the section A at the top thereof and a similar stiffening member D is applied to the section B also at the top thereof. Each stiffening member C, D, may consist of truss members forming a lattice work. The upper section B may be provided with an additional lattice work stiffening member E extending inwardly. The usual closing disk having rollers and stiffening members is shown at F. The gas holder section or shell member A, with its stiffening member C, and the closing disk F, together constitute a complete gas holder and may be constructed to serve as a complete gas holder unit until such time as increased storage capacity becomes necessary. At such time the section B may be added, preferably by erecting a course of panels at the upper edge of the gas holder A and then building successive courses of panels in an upward direction. As such courses are fastened into place and made tight, the closing disk F may be moved upwardly for instance as indicated by dotted lines in Fig. 1 so as to give immediate increase of storage capacity and also to serve as a working platform for the workmen to facilitate the erection of successive courses of panels. The provision of a stiffening member is necessary to give sufficient resistance to the section A against wind pressure. By providing an exterior stiffening member such as C, it is made possible progressively to in-

crease the height of the gas holder, using the disk as a working platform and simultaneously increasing the storage capacity of the gas holder, without the necessity of removing any portion of such stiffening member as the work progresses and thus sacrificing strength and resistance of the structure as a whole. When the upper shell member section B has been raised to the desired height, another exterior stiffening member D is preferably added in order to give added powers of resistance against wind pressure to the enlarged structure. If and when the structure has attained the greatest height to which it may safely be extended or which may be desired, the additional strengthening member E is preferably added.

It is, of course, not necessary that the stiffening members C and D should be located exactly at the upper portions of the respective sections A and B as each stiffening member may be located below the upper line of the section which it is designed to protect, but preferably not more than one-third of the height of such section. It may be found that under certain circumstances and conditions the stiffening member C may be sufficient to give to the gas holder composed of the shell member sections A and B the rigidity necessary to resist wind pressure and other stresses so that the stiffening members D and E may be omitted entirely or only one of them may be employed.

As stated above, the stiffening or reinforcing means for shell member A should be located externally thereof so as not to interfere with the movement of the disk F into the added shell member section B, there being no permanently necessary reinforcing or other members extending within shell member A whose removal, upon the addition of shell member section B, would affect the strength or rigidity of the gasometer.

Various changes in the specific form shown and described may be made within the scope of the claim without departing from the spirit of my invention.

I claim:

100 A gasometer of the disk type, comprising a shell having a movable disk closure therein, a stiffening member attached to and ex-

tending externally on said shell and capable of supporting an additional shell section superposed on said shell and attached thereto to thereby increase the capacity of the 5 gasometer, and a sealing disk located within said shell member, there being no permanently necessary reinforcing means extend-

ing within said shell member, so that said disk may be raised without permanent necessary obstruction to a position within said 10 additional section.

In testimony whereof I have hereunto set my hand.

KONRAD JAGSCHITZ.
